(57) CLAIM

The ornamental design for the football clothing package, as shown and described.

DESCRIPTION

FIG. 1 is a perspective view of the football clothing package; FIG. 2 is a front elevation view of the football clothing package shown in FIG. 1;

FIG. 3 is a rear elevation view of the football clothing package shown in FIG. 1;

FIG. 4 is a right elevation view of the football clothing package shown in FIG. 1, the left side being a mirror image thereof;

FIG. 5 is a top elevation view of the football clothing package shown in FIG. 1;

FIG. 6 is a bottom elevation view of the football clothing package shown in FIG. 1; and,

FIG. 7 is a perspective view of the football clothing package supported within the phantom image of exemplary paper-board packaging.

The broken lines showing environment are for illustrative purposes only and form no part of the claimed design.
